UNITED STATES PATENT OFFICE.

JAMES HARDEN, JR., OF NEW YORK, N. Y.

DESIGN FOR A DISPLAY-CASE.

42,461.

Specification for Design.

Patented May 7, 1912.

Application filed December 1, 1911. Serial No. 663,456. Term of patent 7 years.

To all whom it may concern:

Be it known that I, JAMES HARDEN, Jr., a citizen of the United States, residing in the borough of Manhattan, in the city, county, and State of New York, have invented a new, original, and ornamental Design for Display-Cases, of which the following is a specification, reference being had to the accompanying drawing, forming part thereof.

The figure is a perspective view of a display case showing my new design.

I claim:

The ornamental design for a display case, as shown.

JAMES HARDEN, JR.

Witnesses:

T. F. BOURNE,
MOSES SALMACH.
